UNITED STATES PATENT OFFICE

122,407

DESIGN FOR A CONDIMENTS DISPENSER

Willard P. Hull and Thelma L. Hull,
Portland, Oreg.

Application August 7, 1939, Serial No. 86,497

Term of patent 3½ years

To all whom it may concern:

Be it known that we, Willard P. Hull and Thelma L. Hull, citizens of the United States, residing at Portland, county of Multnomah and State of Oregon, have invented a new, original, and ornamental Design for a Condiment Dispenser, of which the following is a specification, reference being had to the accompanying drawing, forming a part thereof.

In the drawing:

Figure 3 is a side elevational view thereof, it being understood that the opposite side is the same as the side shown.

We claim:

The ornamental design for a condiment dispenser, as shown and described.
